(57) **CLAIM**

The ornamental design for a running board for a snow vehicle, as shown and described.

DESCRIPTION

FIG. 1 is a top left isometric view of a running board for a snow vehicle showing our new design for the present application.

FIG. 2 is a front view of a running board for a snow vehicle with the rear end of the running board elevated above the front end of the running board.

FIG. 3 is a rear view of a running board for a snow vehicle with the rear end of the running board elevated above the front end of the running board.

FIG. 4 is a right side view of a running board for a snow vehicle.

FIG. 5 is a left side view of a running board for a snow vehicle.

FIG. 6 is a top-down view of a running board for a snow vehicle.

FIG. 7 is a bottom view of a running board for a snow vehicle; and,

FIG. 8 is a top left isometric view of a running board for a snow vehicle.

The broken lines in the drawings depict portions of the running board for a snow vehicle that form no part of the claimed design.
